229,518

DISPENSING PIN FOR MEDICAL ADMINISTRATION EQUIPMENT

Albert Frank Bujan, Waukegan, Ill., assignor to Abbott Laboratories, North Chicago, Ill.

Filed Oct. 26, 1971, Ser. No. 192,703

Term of patent 7 years

Int. Cl. D24—04
U.S. Cl. D83—12 A

FIG.3

FIG.2

FIG.1

FIG.4

FIG.5

FIG. 1 is a right side elevational view of a dispensing pin for medical administration equipment showing my new design;

FIG. 2 is a front elevational view;

FIG. 3 is a top plan view;

FIG. 4 is a rear elevational view; and

FIG. 5 is a bottom plan view.

I claim:

The ornamental design for a dispensing pin for medical administration equipment, substantially as shown and described.
